UNITED STATES PATENT OFFICE.

JAMES MASON, OF EYNSHAM HALL, WITNEY, COUNTY OF OXFORD, ENGLAND.

FURNACE FOR BURNING PYRITES.

SPECIFICATION forming part of Letters Patent No. 274,453, dated March 20, 1883.

Application filed July 29, 1882. (No model.) Patented in England June 16, 1882, No. 2,851.

To all whom it may concern:

Be it known that I, JAMES MASON, a subject of the Queen of Great Britain, residing at Eynsham Hall, Witney, county of Oxford, England, have invented certain Improvements in 5 Furnaces for Burning Pyrites, (for which I have obtained a patent in Great Britain, dated the 16th day of June, 1882, No. 2,851,) of which the following is a specification.

10 This invention relates to improvements in that class of furnaces for burning pyrites in which the pyrites are subjected to heat in an inclined bed, down which they are fed by a series of rollers. According to my said improvements, the cylinders or rollers used in such furnaces, instead of having smooth or continuous flutes or projections along their surfaces, have the flutes serrated or notched or covered with studs or projections regularly or 15 irregularly disposed and of any convenient figure.

Figures 1, 2, 3, 4, and 5 of the accompanying drawings represent portions of such cylinders or rollers, illustrating under various 20 modifications my improvements in this respect. Fig. 1 represents the disposition of the projections which I prefer. Fig. 2 is a transverse section of the same drawn to a larger scale. The studs *a* are cast or otherwise formed 25 on or fixed to the body *A* of the cylinder or roller, which is formed with turned ends or journals to project to outside the furnace and there be mounted on bearings, and provided with means for driving them, as is usual or 30 convenient. The said studs *a* are disposed in rows parallel to the axis of the cylinder or roller, by which disposition they may be readily cleared of any obstruction without stopping the furnace, which clearance can be effected 35 by a pointed steel rod introduced through cleaning-holes made for the purpose in either side or both sides of the furnace, over the axle of each cylinder or roller, the said steel rod being worked along the lines of spaces *x* between the teeth or projections *a*. Fig. 3 represents 40 the studs or projections arranged in helical lines around the cylinder or roller *A*. Fig. 4 represents the studs or projections *a* formed by serrated longitudinal flutes *b*. Fig. 5 represents 45 the said studs or projections *a* as being formed by serrated rings or annular flues *c*. The studs of the cylinders or rollers may be

placed so as to interlace with those of the adjacent ones, or a series of serrated rings may be arranged alternating with and passing into 55 corresponding recesses in the adjacent cylinders or rollers.

In certain cases—for example, where it is desired to treat poor cuprous pyrites—I arrange a fire-place underneath the lower end of 60 the bed of the furnace.

Fig. 6 represents a longitudinal section of a furnace provided with this improvement. The furnace-bed *D D*² has at *e* the temporary fire-place employed for the purpose of heating up 65 and starting the furnace, communicating by the flues *e*² with the upper end of the furnace, through which the products of combustion pass and out by the flues *e*³ *e*³ to the chimney. Toward the lower end of the furnace I form 70 another and permanent or continually-acting fire-place, *f*, from which the products pass by the flue *f*², situated underneath the lower part of the bed of the furnace, and away by the flue *f*³ to the chimney. By the fire in the fire-place 75 *f* the lower cylinders are continually maintained at a dull red heat, the distance of the said fire-place *f* from the lower ends of the furnace depending upon the total length of the furnace and number of cylinders used, so as to 80 heat the number of the lower cylinders that require such heating. By this means in a given sized furnace I am able to extract about one per cent. more sulphur from the ore than has hitherto been practicable and to increase the 85 proportion of the soluble copper to the insoluble copper.

In order to enable the furnace to be constructed of considerable length without the necessity for using a shaft or shafts of inconvenient weight to drive the cylinders or rollers, I separate the whole number of cylinders or 90 rollers in the furnace into sets or series, each moved by its own shaft or shafts. To facilitate this arrangement I construct the furnace 95 with the bed in two or more portions and at different elevations, so that although the several beds thus formed are in parallel planes—that is to say, have the same inclination—yet between the parts which are to be driven by separate shafts there is a drop or “set-off,” as at *g* in Fig. 6, in which figure I have shown but two beds having separate driving-shafts; but 100 it will be understood that there may be more

than two if the length of the furnace should render it necessary or desirable. The series of cylinders or rollers in the part D are driven by gearing on the shaft h, and those in the part D² are driven by gearing on the shaft i. There may be shafts on either or on both sides of the furnace, and when shafts are used on both sides they may drive alternate cylinders or rollers on each side or otherwise, as may be convenient. The shafts h i may be driven by one engine or motor, either by transmitting the motion of one shaft to the other or by other means. The rolls or cylinders may be geared to their shafts in any suitable way— as, for example, by worm-gearing, as shown in my Patent No. 241,685, dated May 17, 1881.

The arched construction of the lower part of the furnace gives facility for the hereinbefore-described arrangement of shafts.

I am aware that heretofore rollers having spikes or teeth have been used in furnaces to aid in feeding and stirring the ore; but in the furnace herein described for treating pyrites ores the inclined series of rollers form a traveling bed for slowly carrying the ore through the roasting-chamber. In operation the ore is ignited by the temporarily-acting fire-place at the upper end of the furnace, and the burning ore is gradually fed down over the top of the rolls or cylinders, which are rotated at a proper speed, the heat of the lower rolls of the series being maintained by the permanently-acting fire-place at the lower end of the furnace.

For a fuller description of the operation of the furnace reference may be had to my Patent No. 241,685, above named, and to the roasting-furnace therein described, upon which the present invention is an improvement.

I claim—

1. In a furnace for burning pyrites, the series of rollers constituting a traveling bed for feeding forward the ore under treatment, the said rollers being provided with projections, studs, serrated rings, or ribs, substantially as described. 40

2. In a furnace for burning pyrites, the inclined series of feed rollers or cylinders constituting a traveling bed for the ore, said rollers or cylinders being provided with studs or projections, substantially as described. 45

3. In a furnace for burning pyrites, the feed rollers or cylinders constituting a traveling bed for the ore, said rollers or cylinders being provided with studs or projections arranged in rows parallel with the axes of the rollers, substantially as and for the purpose set forth. 50

4. The feed cylinders or rollers arranged in different but parallel inclined planes, each series of rollers being operated by a separate shaft or shafts, substantially as described. 55

5. In a furnace for roasting pyrites ores, having a traveling bed composed of a series of rollers, as set forth, and provided with a fire-place at the upper end for starting the combustion of the ore, the additional fire-place at the lower part of the furnace for keeping the lower rolls of the series at the required temperature, substantially as described. 65

In testimony whereof I have signed my name to this specification in the presence of two subscribing witnesses. 70

JAMES MASON.
